CLAIM

The ornamental design for a finger prosthesis, as shown and described.

DESCRIPTION

FIG. 1 is a perspective view of a finger prosthesis showing our new design;

FIG. 2 is a right side elevation thereof shown on a slightly reduced scale;

FIG. 3 is a bottom plan view thereof;

FIG. 4 is a top plan view thereof;

FIG. 5 is a front perspective view thereof shown on a slightly enlarged scale; and,

FIG. 6 is a rear perspective view thereof.
